TELEPHONE REGISTERING SYSTEM.

1,107,155.

Specification of Letters Patent. Patented Aug. 11, 1914.

Application filed April 15, 1905, Serial No. 255,832. Renewed December 31, 1910. Serial No. 600,279.

To all whom it may concern:

Be it known that I, EDWARD E. CLEMENT, a citizen of the United States, residing at Washington, in the District of Columbia, have invented certain new and useful Improvements in Telephone Registering Systems, of which the following is a specification, reference being had therein to the accompanying drawing.

10 My invention relates to telephone systems, and has for its object the production of a registering system for use in connection with the telephone circuits.

The desirable features to be attained are 15 the following: a record of the particular operator who handled a particular volume or business; a record of each call made and of each call answered by the called subscriber; and if desired a record of the length 20 of time elapsing between the call and the connection, the latter and the answer by the called subscriber, and during the conversation. The importance of these records will be perfectly apparent to every traffic man, 25 and of the operator's record to every manager.

I attain my object, and produce all the 30 features claimed, as well as others which will appear hereinafter, with simple circuits and apparatus confined to the central office and connected with the cord or connective 35 circuits of the exchange.

I provide a selective switch associated 40 with each cord circuit which, upon a connection being made with a line through that cord, will automatically start a movable part over a number of line-identifying contacts, stopping it when that contact is reached corresponding to the line with 45 which connection has been made. A number wheel during this operation has been turned so that the number of the connected line is automatically brought opposite a printing platen, to print the number. Each operator 50 is provided with a distinctive key inserted, when she is on duty, in a switchboard opening, and sending makes and breaks corresponding to the operator's number, to set an auxiliary printing wheel to bring the 55 same in printing position.

The details of my invention will appear from the following description and claims.

My invention is illustrated in the accompanying drawings, wherein—

55 Figure 1 is a diagram showing two sub-

scribers' line-circuits and a central office connecting circuit, with a registering device attached thereto. Figs. 2 and 3 are details of the type wheel and attachments. Fig. 4 shows a piece of tape on which the record is printed. Fig. 5 is a modification of the tape feed mechanism.

Referring to Fig. 1, A and A' are two subscribers' stations shown as connected to a multiple switchboard wired up in accordance with a well known standard scheme of two-wire multiple. Each sub-station is equipped with apparatus usual in common battery systems, which consists of a transmitter T, receiver R, hook H, ringers Q and condenser C. The line-wires from the two sub-stations terminate in a central office in similar apparatus, and therefore only one need be described. The line-wires 1 and 2 extend from the sub-station to the contacts n , n' , of the cut-off relay N, where they are normally extended, the first to the line-relay M and the second to ground. When the relay N is energized the line-wires 1 and 2 are extended through to the contacts j , j' of the answering-jack J by the wires 3 and 4. The cord-circuit consists of the answering-plug P, whose tip p is connected to the tip p' of the calling-plug P' by the strand 7, condenser C, and strand 9. The sleeve p' of the plug P is connected to the sleeve p' of the plug P' by the strand 8, condenser C' and strand 10. Bridged across the strands 7 and 8 is a pair of supervisory relays S, S', which jointly control the supervisory lamp s. 75 Bridged across the strands 9 and 10 are the two supervisory relays S² and S³ jointly controlling the lamp s².

All of the arrangement so far described is old and well known, having been largely 80 used in common battery installations. I have shown my invention in connection with this circuit because it happens to be a convenient system for illustration; but I do not wish to be limited thereby nor am I 85 limited in practice to any particular type of system. My invention is well adapted for any of the common battery systems now known and used.

The type of switch I have chosen to illustrate is that employed quite commonly in automatic exchange systems according to 90 present practice. Its essential features are a spindle carrying a contact wiper and rotating to move said wiper over a series of 95 100 105 110

fixed contacts arranged in a circle having a greater or smaller dimension according to the number of contacts. The circle with its contacts is called a bank or contact bank.

5 The spindle is rotated by means of a ratchet wheel mounted on it and a pawl vibrated by an electro-magnet. This spindle has no idle or normal position, that is the wiper can rest on any contact, for when the switch

10 itself is idle there is no connection of any kind with the wiper. Mounted on the spindle is a type wheel fixed so that when the wiper rests upon any particular line-contact the number of that line on the type wheel will

15 be opposite the tape. There is also added a type wheel D' mounted on a sleeve which revolves on the spindle and is free to move without causing any action of the spindle. This type wheel contains numbers or characters used to designate which operator is occupying the position at a certain time.

Referring now to Fig. 1, Z is the selector switch having a spindle z⁶ mounted for revolution in a foot-step but which may and

25 practically will be in practice horizontal. On this spindle is mounted a collar z⁴, carrying the wiper z⁵, which extends out radially so as to sweep over the circle of contacts as the spindle rotates. At the upper end of the

30 spindle is a type wheel D, bearing on its periphery type numbers or characters raised in relief, there being a number or character on the wheel corresponding to each line having a multiple contact in the bank swept

35 over by the wiper z⁵. Directly under this type wheel there is another type wheel D', bearing on its periphery characters or numerals corresponding to the number of the operators occupying the position. Opposite

40 the two type wheels is a printing magnet W shown as a solenoid magnet with an iron shell and a central plunger carrying the armature w³ at one end and the printing platen w⁵ at the other. Between the plates

45 and the type wheel lies the tape x fed from a roll or spider X, as shown above the wheel, down between the friction or feed rolls w' and w². The feed of this tape is governed by the printing magnet. As I

50 have illustrated it for simplicity, this is accomplished by means of a spring extension arm w³ attached to the armature and provided with a hook or toe which catches into teeth on the periphery of the feed-wheel w'.

55 This may work in either of two ways, both of which would be well enough, represented diagrammatically as shown. First, it may be that the toe on the arm w³, when the armature is retracted, will pull the wheel

60 w' around several teeth depending on the space of the air gap allowed the magnet W, thus feeding the tape a space after the number is printed a second time. Second, the toe may be merely a detent, as shown in Fig.

65 5, and the shaft or arbor of wheel w' be a

driven shaft, that is, provided with a motor as clock work, the speed of the shaft's rotation being predetermined and constant. In this case after the printing magnet has done its work and slightly retracted its

70 armature so as to free the tape from pressure, the latter will be continuously fed until the printing circuit is broken at the end of a conversation. On the retraction of the armature the detent will prevent further

75 rotation of the shaft. The length of the tape fed will thus be a measure of the elapsed time after the number was stamped and furnishing means for getting totals of time use of subscribers' lines.

80 The circuits of my switch are very simple, and the connections to the cord and line-circuits are made without altering or interfering with any of their parts. Taps are taken off the sleeve side of each line and

85 carried to the multiple contacts in the switches of its particular position, there being one switch to each operator's cord-circuit. A tap is also taken from the sleeve side of the cord-circuit, as well as one from the back contact of the calling supervisory

90 relay. These three taps are the only necessary wires to be connected, one tap for a line and two for a cord-circuit. The tap from the back contact of the calling supervisory

95 relay supplies current through the wire 13 to the magnets W' and W when the calling plug is inserted, and it may also be used for the supervisory lamp s⁵, but in that case the lamp and the magnets must be of such resistances that they will not operate on the small normal leakage through the wires 18 and 14. In practice the tap for the lamp is taken from a separate contact, so that the

100 wire 13 is normally ungrounded.

105 Referring now to Fig. 1, the sleeve side of the line No. 4 is connected in multiple to the contacts of the switches in its position by the wire 30. The sleeve 8 of the answering-plug is connected to one terminal of the relay S⁴, the other terminal of which is connected to battery by the wire 12 through the contacts s¹⁸ and s¹⁹ of the relay S⁵. The contact s⁴ of the calling supervisory relay S² is connected to the magnet W' by the wire 13, the other terminal of this magnet as well as one terminal of the magnet W is connected to the contact s²³ of the relay S⁵ by the wire 16, the other terminal of the magnet W being connected to battery through

110 the contacts s¹⁰ and s¹¹ of the relay S¹. One terminal of the rotary magnet S⁶ is grounded, the other terminal being connected to the contact s¹⁶ of the relay S⁴.

115 One terminal of the rotary or interrupting machine G is connected to the contact s¹⁵ of the relay S⁴. One terminal of the relay S⁵ and the contact s²¹ are grounded, the other terminal being connected to the contacts s¹²,

120 s¹⁴ of the relay S⁴ by the wire 17. K rep-

125

130

resents an operator's key similar to those used in connection with the time clocks, as used in factories for registering the time of an employee. This key has the projections 5 or teeth, k^5 , on its edges which when inserted in the jack J^5 will come into contact with the springs k , k' , making and breaking contact with them as the teeth pass. Each 10 operator is provided with a key having different numbers of projections or teeth. This key operates and registers the operator's number on the tape as follows: When placed in the jack it makes and breaks the contacts k , k' , according to the number of 15 projections, k^5 , on the edge of the key. These makes and breaks operate the magnet S' , which causes the sleeve z^2 carrying the number-wheel D' to rotate the number of times corresponding to the number 20 of teeth of the key. This brings the operator's number on the number-wheel opposite the tape, and when the printing magnet W is operated it stamps the operator's number as well as the number of the line on the 25 tape. The key has a long shank, and when first inserted closes the contacts k^2 and k^3 , which in turn close the circuit of the release magnet S^8 . This magnet attracts its 30 armature and engages the sleeve z^2 , acting as a retaining pawl. When the operator leaves the position, she withdraws the key K and opens the contacts k^2 , k^3 , releasing the magnet S^8 , which thereupon releases the sleeve z^2 , which is then carried to its normal 35 position by a suitable tension spring.

The operation of my system is as follows: Subscriber A in calling closes the circuit of the line-relay M through the contacts of the 40 cut-off relay N , closing the local circuit of the lamp m , which glows. The operator upon perceiving the signal inserts the answering-plug P into the jack J . The windings of the relays S' and N are now connected in series. The relay N becoming 45 energized attracts its armatures, disconnects the line-relay M which in turn extinguishes the line lamp m . The line-wires 1 and 2 are now connected to the springs j , j' , of the jack J , through the contacts of the cut-off 50 relay N and the extensions 3 and 4. The relay S' , becoming energized attracts its armature and would cause the lamp s to glow, but the relay S becoming energized also attracts its armature, opening the lamp 55 circuit. The relay S^4 of the register is connected to the strand 8 by the wire 15 and is in parallel with the relay S' , so therefore becomes energized and attracts its armatures. The closing of the contacts s^{10} , s^{12} , 60 closes the circuit of the relay S^6 , which becoming energized attracts its armatures, breaks the contacts s^{18} , s^{19} and closes the contacts s^{17} and s^{10} , which disconnects one terminal of the relay S^4 from battery by 65 breaking contacts s^{18} — s^{19} , and connects it to

the wiper z^5 by closing contacts s^{17} — s^{19} , this closure occurring either before or simultaneously with the break. The contacts s^{18} and s^{25} are closed, and the terminal of the relay S^4 leading to strand 8 is connected directly to battery and relay S' is thereby shunted. The cut-off relay N is now held energized by battery direct by the following path: battery, wire 12, contacts s^{18} , s^{25} , s^{26} , s^{27} , wire 15, strand 8, p' , j' , wire 4, relay N to ground. The relay S^4 is now kept energized by the wiper z^5 which passes over the contacts z^{10} as the spindle z^6 is turned by magnet S^6 , which is energized by the closing of the contacts s^{15} , s^{16} , to connect the interrupting machine G to the wire 19. All contacts z^{10} are grounded through their respective cut-off relays. This circuit of magnet S^4 is then as follows: B, 12, s^{18} , s^{25} , s^{26} , s^{27} , 15, S^4 , s^{19} , s^{17} , 21, z^5 , z^{10} , 30, N , and ground. 80 This spindle will continue to rotate until the wiper z^5 which closes on each contact before breaking the preceding, comes into connection with the contact leading to the line in which the plug is inserted. The instant this happens the relay S^4 becomes short-circuited or shunted by the following circuit: wire 4, j' , p' , strand 8, in which there is practically no resistance, in comparison with the following circuit: wire 30, z^{10} , z^5 , 21, s^{17} , s^{19} , S^4 85 and 15 to the wire 8, also from point 15 to contacts s^{27} and s^{26} , thence to contacts s^{25} and s^{18} , and thence by wire 12 direct to battery. The relay S^4 therefore being short-circuited becomes deenergized, opens the 90 contacts s^{26} , s^{27} , removing the short-circuit from the relay S' , allowing its winding to be in series with the relay N . The contacts s^{15} , s^{16} are broken, disconnecting the interrupting machine, which causes the spindle to at once come to rest. The relay S^5 is held energized after the relay S^4 has become deenergized by the following path: ground, S^5 , wire 17, contacts s^{14} and s^{13} , wire 23, contacts s^{22} , s^{20} , wires 20, 21, wiper z^6 , 105 contacts z^{10} , wires 30, 4, and 8, and to battery through the winding of the relay S' . The relay S^5 is now held energized in parallel with the relay N by current flowing through the relay S' . When the relay S^4 first became deenergized, the circuit of the printing magnet W was closed by the following path: ground, contacts s^{21} , s^{23} , wires 16, 14, s^{11} , s^{10} , wire 18 to battery. Becoming 110 energized it attracts its armatures and presses the tape against the number-wheels D , D' , printing the number of the line connected and also the number of the operator. When the operator completes the connection by placing the calling plug P' into the jack J' and ringing in the ordinary manner, the following conditions are effected: The relay S^8 and the relay N are placed in series. The relay N in attracting its armatures disconnects the line-relay M and connects the 115 120 125 130

4 called line to the springs j, j' of the jack J' . The relay S^3 attracting its armature closes the circuit of the lamp s^5 , causing it to glow. It also closes the circuit of the magnet W' , which attracts the arm w . The circuit of magnet W' is as follows: B, 12, 5 $s^8, s^9, s^3, s^4, 13, W', 16, s^{23}, s^{21}$, and ground. When the called subscriber answers, the relay S^2 becomes energized, extinguishing the lamp s^5 and at the same time releasing magnet W' . This magnet when deenergized releases the arm w , which comes in contact with the tape x and prints a character or number, or it can perforate the 10 tape as may be desired. This distinguishing mark on the tape opposite the number of the line calling gives a record showing that the called party has answered. In case there should be no distinguishing mark opposite the number, it is an indication that the called party did not answer. We now have a record on the tape showing the number of the calling subscriber and the number of the operator, and a mark showing that the 15 called subscriber has answered. At the end of the conversation, the subscribers in hanging up their telephones open their respective line-circuits and deenergize the relays S and S^2 , causing the lamps s, s^5 to glow. The 20 operator noticing these signals takes down the connection, and the cut-off relays N , of both subscribers' lines, become deenergized, and cut on their respective line-relays and disconnect the lines from the jacks. 25 The relay S^6 of the register being now deprived of its current supply, through the relay S' , becomes deenergized. The relay S^4 is again connected to battery through the contacts s^{18}, s^{19} and the breaking of the 30 contacts s^{17}, s^{19} and leaves the wiper z^5 free from all connections, so that it can rest on any contact without causing interference of any kind. The contacts s^{21} and s^{23} being broken, the printing magnet W becomes deenergized and the arm w^3 in moving back to 35 its normal position engages the friction wheel w' , causing it to move a short distance, which in turn moves the tape to allow for the next number being printed.

50. What I claim is:—

1. A telephone registering system comprising an automatic selector switch containing line-identifying terminals and a wiper coöperating therewith, a register associated with the switch, means to actuate the switch and register in making a connection, to select the line connected, means to record the call on the register charged to the line selected, and means to indicate if 55 the call was answered, substantially as described.

2. A telephone registering system comprising an automatic selector switch containing line-identifying terminals and a 60 wiper coöperating therewith, a register as-

sociated with the switch, means to actuate the switch and register in making a connection, to select the line connected, means to record the call on the register charged to the line selected, and means to indicate if 70 the operator or connective device through whom or which the connection was effected, together with setting means for said indicating means individual to each operator, substantially as described. 75

3. A telephone registering system comprising an automatic selector switch containing line-identifying terminals and a wiper coöperating therewith, a register associated with the switch, means controlled through said wiper to actuate the switch and register in making a connection, to select the line connected, means to record the call on the register charged to the line selected, and means normally dissociating the 80 switch wiper from said actuating means, so that the latter may be left indifferently upon any contact when idle, substantially as described.

4. A telephone registering system comprising an automatic selector switch containing line-identifying terminals and a wiper coöperating therewith, a register associated with the switch, means controlled through the wiper to actuate the switch and 90 register in making a connection, to select the line connected, means to record the call on the register charged to the line selected, and a dissociated relay acting when the 95 circuits are idle to cut off the switch wiper from said actuating means, and when a connection is effected to associate the same, substantially as described.

5. A telephone registering system comprising an automatic selector switch containing line-identifying terminals and a wiper coöperating therewith, a register associated with the switch, means to actuate the switch and register in making a connection, to select the line calling, means to record the call when said line is selected, and means brought under the control of the subscriber called to charge the call to the line calling when the connection is completed 105 and the call is answered, substantially as described. 110

6. A telephone registering system comprising an automatic selector switch containing line-identifying terminals and a wiper coöperating therewith, a register associated with the switch, means to actuate the switch and register in making a connection, to select the line calling, means to record the call when said line is selected, and means brought under the control of the 120 subscriber called in completing the connection, to determine whether or not the call shall be charged, substantially as described.

7. A telephone registering system comprising an automatic selector switch con- 130

taining line-identifying terminals and a wiper coöperating therewith, a register associated with the switch, an actuating magnet for the switch, a source of current supply for the magnet, a controlling relay, a registering magnet actuated during the connection to record the designation of the line calling, and a second registering magnet actuated when the calling subscriber answers to indicate that fact, substantially as described.

8. A telephone registering system comprising an automatic selector switch having line-identifying terminals and a coöperating wiper terminal, a motor for moving said switch, a controlling relay, a printing register associated with the switch and having designations corresponding to the terminals of the switch, a printing magnet therefor, 20 and a second printing magnet operated only when the call is answered, substantially as described.

9. In a telephone exchange registering system, an automatic selector switch Z, containing line terminals z^1 , and a wiper z^2 , a printing wheel D, a motor for revolving the switch, a printing magnet W, controlling relays S^4 and S^5 , and a second printing magnet W' to indicate when the call is answered, 30 together with circuit connections from the line terminals to the respective lines or associated circuits, and from the controlling relays to the cord or connective circuit with which the switch is associated, substantially 35 as described.

10. In a telephone registering system, a combined register and selector comprising a spindle, selective switch contacts moved by said spindle, a printing wheel carried by 40 the spindle and set to expose a number corresponding to the contacts made in any given position of the spindle, a second printing wheel loosely mounted on the spindle and bearing designations for one or more operators, magnetic controlling means independent of the switch controlling means for setting the second printing wheel, and circuits therefor under the control of the operator or operators, substantially as described.

50 11. A telephone registering system comprising in combination, a register common to a plurality of lines, said register having means actuated by a calling subscriber for registering his number, and means actuated by the called subscriber for registering an answered call, together with operatively connected means actuated by the operator for registering the operator's number.

12. A telephone register common to a plurality of lines, means for registering the 60 number of the calling subscriber and independent means jointly controlled by an operator and the called subscriber for registering an answered call.

65 13. A telephone exchange system having

a plurality of lines, and means for interconnecting them, a register common to a plurality of lines comprising means for automatically registering the number of the calling subscriber and means for automatically 70 registering an answered call.

14. A telephone register common to a plurality of lines comprising means to register the number of a calling subscriber, means to register the number of the operator and 75 means for registering an answered call, operatively associated together.

15. A telephone register common to a plurality of lines comprising means for recording the number of the calling subscriber, 80 automatic means for modifying said record to indicate an answered call, together with manual means individual to an operator for causing the operator's individual number to be indicated on said record.

85 16. A telephone register system comprising registering means and means whereby the register is controlled by act of the operator in answering a call to record a call, and means controlled by the aforesaid register controlling means and controlled also by the called subscriber for modifying the record to indicate an answered call.

17. In a telephone system, a plurality of lines, means for interconnecting the same, 95 and a call recorder having a recording mechanism rendered active for each call made to identify the same with a supplemental recording mechanism rendered active to identify the same call when it is answered by the 100 called subscriber only.

18. In a telephone exchange system, a plurality of subscribers' lines, a recorder common to said lines, means for recording a calling subscriber's number, and means controlled by the called subscriber for recording 105 that the call was answered by the called subscriber.

19. In a telephone exchange system, a plurality of subscribers' lines, means for interconnecting the same, a recording member, means for setting the same to expose and record the number of a line calling, and means controlled by a called subscriber to record 110 the fact that the call was answered.

20. In a telephone exchange system, a plurality of subscribers' lines, means for interconnecting the same, and a recording system therefor, comprising a single recorder common to a plurality of lines, means becoming 120 operative in making connection with a calling line to select and record the number thereof, and further means controlled over the called line to record the fact that the call was answered.

125 21. In a telephone system, a plurality of lines to be interconnected, means for interconnecting the same, and a recorder common to a plurality of subscribers' lines, means associated with a calling subscriber's line to 130

control the register and record the number of the calling line, together with means controlled over the called subscriber's line to record a supplemental indication if the call was answered.

22. In a telephone exchange system, a plurality of subscribers' lines, means for interconnecting them, a recorder common to a plurality of lines, a printing wheel and a printing magnet adapted when a line is calling to select and print the number of that line, and a supplemental printing device and printing magnet controlled by the called subscriber in every case to indicate that the call was answered.

23. In a telephone exchange system, a recording system for telephone exchanges, including a selector switch, a motor for said

switch, means for actuating said motor when a line calls in, and a recording device 20 brought into circuit by the connections effected by the switch and adapted to record the number of the calling line.

24. In a telephone exchange system, a plurality of lines and means for interconnecting them, and a common recorder comprising two elements, one becoming active in the initiation of a connection and the other in the completion of the same only.

In testimony whereof I affix my signature 30 in presence of two witnesses.

EDWARD E. CLEMENT.
